ATTORNEY.

UNITED STATES PATENT OFFICE.

OTTO A. BANNER, OF MILWAUKEE, WISCONSIN, ASSIGNOR TO THE FALK CORPORATION, OF MILWAUKEE, WISCONSIN, A CORPORATION OF WISCONSIN.

OIL ENGINE.

Application filed March 17, 1922. Serial No. 544,413.

This invention relates to oil engines, and particularly to those of the solid injection or pump spray type, although certain novel features thereof may be advantageously employed in other types of internal combustion engines.

One object of the invention is to improve the combustion and thermal efficiency in engines of the type referred to.

10 Other objects and advantages will later appear.

Embodiments of the invention are illustrated in the accompanying drawings, in which:

15 Figure 1 is a fragmentary sectional view of an engine cylinder embodying the novel features of the present invention.

Figure 2 is a view taken substantially on the line 2—2 of Figure 1, with the cylinder head removed.

20 Figure 3 is a view similar to Figure 2 illustrating a somewhat different method of injecting the fuel.

For convenience of illustration and explanation, the invention is shown and will be described as embodied in a four-cycle oil engine of the vertical type, although it is applicable to two-cycle engines and to engines of the horizontal type.

25 The engine illustrated in Figures 1 and 2 comprises a cylinder 10 having a cylinder head 11 both water jacketed in the usual manner. The cylinder head contains the usual exhaust and air inlet valves 12 and 13, respectively. The space between the cylinder head and cylinder proper, however, is divided by a partition 14, preferably water-cooled as indicated at 15, and having a restricted passage or throat 16, through which

30 air and other gases are caused to pass during the reciprocation of the piston 17 within the cylinder.

The partition 14 in the engine shown is formed as a part of a member 18 interposed beneath the cylinder head and cooperating therewith to form an elongated, substantially flat chamber 19 extending transversely of the cylinder and of sufficient length and width to accommodate the valves 12 and 13. The fuel is introduced into the chamber in such manner as to form a substantially flat spray conforming in a general way to the shape of the chamber.

35 One method of introducing the fuel is illustrated particularly in Figure 2. As indi-

cated in this figure, two injection nozzles 20 are employed, one at each end of the chamber. These are of the type described in the copending application of O. A. Banner and Jacob Schlumberger, filed March 17, 1922, Serial Number 544,427. Each includes a pair of fuel discharge ducts arranged to produce a pair of convergent fuel jets which meet at a point and spread out to form a substantially flat spray of approximately uniform density within an end of the chamber.

The fuel is delivered to the nozzles through pipes 21 in a sudden ram-like charge immediately prior to compression 70 dead center, when movement of the piston has practically ceased, and when the flow of air through the restricted passage 16 has ceased. Each flat spray is directed toward the central portion of the chamber where it 75 meets with the other flat spray to form a narrow concentrated fuel cloud which extends across the chamber. As the sprays are projected through the body of hot compressed air in the chamber a relatively light 80 fuel mist is formed about the surfaces thereof, due to the frictional contact of these surfaces with the surrounding air. This light fuel mist is readily vaporized and starts burning almost simultaneously with 85 the initial injection. This initial combustion effects the vaporization of the coarser fuel particles contained in the concentrated fuel cloud and prepares the same for quick 90 burning. Actual burning of the fuel in the concentrated cloud, however, can not take place until it has been brought in contact with the oxygen of the air necessary to carry out the chemical reaction.

This mixture and contact of the air with 95 the fuel in the concentrated cloud is effected, during the early part of the working stroke, by the turbulence set up in the chamber, restricted passage, and piston space at that time. This turbulence is started by the initial combustion of the fine fuel mist and is continued and increased as the piston starts its working stroke and permits the contents of the chamber to pass through the restricted passage into the piston space. 100 Thus, although initial combustion occurs in the chamber and almost simultaneously with the injection of the fuel, yet the major portion of the combustion occurs within the restricted passage and piston space, as the 105 110

fuel in the concentrated cloud is mixed with the oxygen of the air flowing from the chamber to the piston space.

It will be noted that in the engine shown in Figure 1 provision is made for retaining a portion of the air within the working portion of the cylinder instead of forcing all the air through the throat 16 into the chamber 19. This may be accomplished in 10 various ways, but in the engine shown the piston 17 is hollowed out, as at 23, for this purpose. Thus a body of air is maintained beneath the partition 14 at compression dead center, which is effective to insure prompt 15 combustion of any unburned fuel projected from the chamber through the throat 16 during the working stroke.

Another method of introducing the fuel into the chamber 19 is illustrated in Figure 3, in which two injection nozzles 20' are employed in each end of the chamber. These nozzles are of a well known form designed to produce single jets of fuel spray. They are arranged in substantially parallel pairs 25 so that the fuel jet from one will merge into the other to produce in effect a single flat spray spread out across the chamber 19. The injection of the fuel is timed to occur, as in the method above described, immediately 30 prior to compression dead center.

Various changes may be made in the embodiments of the invention hereinabove described, without departing from or sacrificing any of the advantages of the invention 35 as defined in the appended claims.

I claim:

1. In an internal combustion engine the combination of a cylinder, injection nozzles at opposite sides thereof for producing substantially flat impacting fuel sprays transversely thereof, a chamber enclosing said sprays and substantially conforming to the shape thereof, and a restricted passage between said chamber and said cylinder intermediate the ends of said chamber.

2. In an internal combustion engine the combination of a cylinder, injection nozzles at the opposite sides thereof for producing substantially flat impacting fuel sprays transversely thereof, a chamber enclosing said sprays and substantially conforming to the shape thereof, means for cooling the walls of said chamber, and a restricted passage between said chamber and said cylinder intermediate the ends of said chamber.

3. In an internal combustion engine the combination of a cylinder, injection nozzles at the opposite sides thereof for producing substantially flat impacting fuel sprays transversely thereof, a chamber enclosing 60 said sprays and substantially conforming to the shape thereof, inlet and exhaust valves opening into said chamber through one wall thereof, and a restricted passage through the opposite wall of said chamber intermediate 65 the ends thereof in communication with the working portion of said cylinder.

4. In an internal combustion engine the combination of a cylinder having a cylinder head, intake and exhaust valves in said head, 70 a water cooled partition in said cylinder cooperating with said head to form an elongated chamber extending transversely of said cylinder, the transverse sectional area of said chamber being substantially rectangular, a 75 restricted passage through said partition, and airless fuel injection nozzles at the ends of said chamber for directing substantially flat fuel sprays toward the center thereof.

5. In an oil engine the combination of a 80 cylinder having a relatively shallow elongated chamber extending transversely thereof, a restricted passage between said chamber and the working portion of said cylinder, means for cooling the walls of said chamber 85 and passage, and airless fuel injection nozzles at opposite ends of said chamber for producing substantially flat impacting fuel sprays which meet to form a narrow elongated cloud of concentrated fuel mist adjacent said passage substantially at compression 90 dead center.

6. In an oil engine the combination of a cylinder having an elongated chamber extending transversely thereof, said chamber 95 being substantially rectangular in transverse section and having a restricted passage intermediate the ends thereof communicating with the working portion of said cylinder, means for cooling the walls of said chamber and said passage, and airless fuel injection nozzles at opposite ends of said chamber for producing substantially flat impacting fuel sprays which meet to form a narrow elongated cloud of concentrated fuel mist adjacent said passage substantially at compression 100 dead center.

In witness whereof, I hereunto subscribe my name this 2nd day of March, 1922.

OTTO A. BANNER.
